UNITED STATES PATENT OFFICE.

CLYDE G. SAMS, OF DE NOYA, OKLAHOMA.

PUMP JACK.

Application filed December 3, 1925. Serial No. 72,974.

This invention relates in general to pump jacks especially adapted for use with wells and aims to provide a simple and durable type of pump jack which will apply straight 5 vertical lift to the polish rod, thereby minimizing the wear on the stuffing box and precluding the breaking of the tubing.

A further object is to provide a device of this character having these advantages and 10 which effectively transmits the motion from the walking beam of the pump jack to the polish rod and yet is entirely safe in operation and easy and comparatively inexpensive to manufacture and apply.

15 Other objects and advantages reside in certain novel features of the construction, arrangement and combination of parts which will be hereinafter more fully described and particularly pointed out in the 20 appended claims, reference being had to the accompanying drawings forming a part of this specification, and in which:

Figure 1 is a fragmentary view in side elevation showing one embodiment of the 25 invention,

Figure 2 is a detail perspective view of the lifting head embodied in the present invention,

Figure 3 is a view of the rear side of the 30 head shown in Figure 2, and

Figure 4 is a view showing a modified form of head.

Referring to the drawings, the numeral 1 designates generally a pump jack which 35 has a standard 2 suitably braced, as at 3, and provided with a bearing 4 for a walking beam 5. The walking beam 5 may have a counterbalance 6 carried thereon and may be oscillated in any conventional manner.

40 A polish rod is designated at 7. The present invention resides in the novel means of transmitting the motion from the walking beam to the polish rod and comprises a lift beam, designated generally at 10, a cable 11 connected to the head 10 and a clamp 12 secured to the polish rod and connected to the cable 11.

The head 12 comprises a curved body plate 12 having an internal rearwardly di-

rected enlargement 13 at its upper end and 50 also having a rearwardly directed and centrally located web 14 integral therewith and with the enlargement 13. The web 14 is provided with a transverse opening 15 whereby it may be bolted or otherwise suitably secured to the walking beam, as indicated at 16 in Figure 1. The enlargement 13 rests on the members making up the walking beam and the web 14 is located between 55 these members. The plate 12 has its rear face abutting the forward ends of the member of the walking beam. In this way the head is firmly and rigidly mounted on the walking beam. The front face of the plate 12 is provided with a pair of spaced grooves 17 which extend from the bottom edge of the plate up and through the top thereof. The upper ends of the grooves 17 are connected by a semi-circular groove 18 provided in the top or upper end of the head 10. 70 The cable 11 is doubled and has its bight portion received in the groove 18 and held in place by the walls of the groove. The two sections of the cable, designated at 18^a, extend through the groove 17 of the plate 75 12 and the ends of the cable are suitably fastened to the clamp 12. In between the grooves 17 the plate 12 is provided with a lengthwise groove 19. It is to be noted that the grooves 17 and 19 follow the arcuate or 80 curved shape of the plate 12.

With this arrangement when the walking beam 5 is oscillated its arcuate motion will be transmitted into a straight line motion by the head 10 and cable 11 so that the polish rod 7 will be reciprocated in a straight line. This relieves the polish rod and tubing of severe stresses and also relieves the stuffing box through which the polish rod operates from wear. By relieving the stuffing box of excessive wear leaking of oil, gas, or water is prevented.

As shown in Figure 4 the rearwardly directed enlargement of the curved body plate may be rounded, as shown at 13^a, and the web 95 may be extended rearwardly as indicated at 14^a and provided with a plurality of laterally projecting lugs 25 on both of its sides.

The lugs 25 co-act with the walking beam to aid the rivets 26 in securing the head and walking beam in assembly.

I claim:—

• A pump jack for use in reciprocating polish rods and including a walking beam, a lifting head including a curved plate having a central rearwardly directed web secured to the walking beam between the mem-

bers thereof, whereby to prevent lateral displacement of the lifting head, said lifting head also having laterally extending projections engageable with the members of the walking beam to prevent vertical displacement of the lifting head, and a cable connected to the head extending over the curved plate and connected to the polish rod. 10 15

CLYDE O. SAMS.
